(57) **CLAIM**

The ornamental design for a 360 degree lamp, as shown and described.

DESCRIPTION

FIG. 1 is a front view of a 360 degree lamp showing my new design.

FIG. 2 is a back view of the 360 degree lamp.

FIG. 3 is a left side view of the 360 degree lamp.

FIG. 4 is a right side view of the 360 degree lamp.

FIG. 5 is a top view of the 360 degree lamp; and,

FIG. 6 is a bottom view of the 360 degree lamp.

The elements shown in broken lines are for illustrative purposes only and form no part of the claimed design.
